Primary Examiner—Robin V. Taylor*Attorney, Agent, or Firm*—Swabey Ogilvy Renault**[57]****CLAIM**

The ornamental design for a clothes line separator, as shown and described.

DESCRIPTION

FIG. 1 is a perspective view of the clothes line separator showing my new design;

FIG. 2 is a front elevational view thereof;

FIG. 3 is a left side view thereof, the right side view being a mirror image;

FIG. 4 is a rear elevational view thereof;

FIG. 5 is a top plan view thereof, the bottom plan view being identical;

FIG. 6 is a perspective view of another embodiment showing my new design;

FIG. 7 is a front elevational view thereof;

FIG. 8 is a left side view thereof, the right side view being a mirror image;

FIG. 9 is a rear elevational view thereof; and,

FIG. 10 is a top plan view thereof, the bottom plan view being identical.
